KNITTED FABRIC AND PROCESS FOR
KNITTING THE SAME

John Lawson, Bristol, and Robert H. Lawson,
Pawtucket, R. I., assignors to Hemphill Com-
pany, Central Falls, R. I., a corporation of
Massachusetts

Application January 23, 1933, Serial No. 653,150

9 Claims. (Cl. 66—180)

This invention relates to knitted fabrics and processes for knitting the same, being more particularly directed to hosiery of the so-called seamless and other types wherein are knitted stripes or other figures or designs, extending generally lengthwise of the stocking and characterized by the knitting-in of a supplemental yarn or yarns in addition to the main or body yarn and more specifically to the knitting of stripes or figures by means of a wrapping of yarn or thread fed to certain selected needles in each course of knitting, in the manner disclosed in the patent to Lawson and Lawson 1,702,608, February 19, 1929, of which the present application is a continuation as to all common subject matter. This application is also a continuation, as to all common subject matter, of application Ser. No. 333,318, filed January 18, 1929.

For purposes of illustration, Figs. 2-6 of the drawings, which show the inner or rear faces of the several fabrics, show body yarns as well as plating yarns in the plain plated wales, and all three yarns—including the wrap stripe yarn—in some of the wrap stripe wales; although actually the body yarns alone show, or show more prominently, at the inner faces of the fabrics. Of course, where reverse plating occurs the body yarn shows at the face wales, and the plain plating yarn on the inner or rear face of the fabric.

In the accompanying drawings:

Fig. 1 shows a side view of a half hose or stocking having stripes knitted therein, which stripes extend lengthwise of the leg and foot portions, the half-hose or stocking also being shown as having stepped or broken designs;

Figs. 2, 3, 4, 5 and 6 disclose inner or rear face views of fabrics, showing variations in the structures of the stitches particularly where the stripes are knitted, all forms showing the floating of certain of the knitting yarns or threads back of the wrapping of yarn or thread forming the stripe or other figured design;

Fig. 7 is a view of a few wales and courses of a fabric showing stepped designs;

Fig. 8 is a view of a few wales and courses of a fabric similar to Fig. 7 but showing a single wrap stripe wale following which are shown spaced, wrap stripe wales; and

Fig. 9 is a view somewhat similar to Fig. 8 but showing the wrap stripe wales as having wrap threads knitted therein.

Fig. 10 shows to a greatly enlarged scale a fabric knitted as in Fig. 4, but wherein the wrap ornamental portion is somewhat of the shape indicated at Fig. 1 but being a solid pattern.

When knitting the so-called lap stripe with an additional wrapping of yarn or thread the main or body yarn is also knitted by the needles that knit the wrapping yarn. If two yarns or threads only are fed to the needles, the lap stripe shows clearly; but if it is desired to combine the lap stripe with reverse plating then it becomes difficult to knit the main, the plain plating and the wrapping yarns, when knitting wide stripes, without the plain plating yarn breaking the continuity of the lap stripe.

The various forms of the fabrics disclosed in the drawings and specification all have two yarns, namely, a main or body yarn and a plain plating yarn, both yarns being knit-in throughout the wales not within the lap stripe areas, designs being knitted by reversing the body and plain plating yarns, as indicated at D, Fig. 1, in the wales not supplied with the lap stripe plating yarn; or the body yarn may be knit-in throughout and the plating yarn substantially throughout but floated back of the body yarn where designs or other figured effects are desired as at E, Fig. 1, the body yarn showing upon the face of the fabric at the wales where the plain plating yarn floats.

During the knitting of the lap stripe, the plain plating yarn is floated back of all the lap stripe wales or some of them only, whereby, at said wales, not more than two yarns will be knit-in, the plain plating and in some cases also the main 30 yarn or thread floating back of such wales together with the rear stretches of the lap stripe plating yarn. The body yarn even where knit-in with the lap stripe yarn does not show through on the front face of the fabric, the lap stripe or 35 reinforcing yarn effectively plating thereover, and overcoming the objection of imperfect plating more or less apparent when knitting wide stripes with the lap stripe plating, plain plating, and body yarns all knit-in at the same wales.

Fig. 1 of the drawings shows a striped stocking or half-hose indicated generally by the reference character A, said half-hose having knitted there-in vertical stripes B some of which span more wales than the others. At C are shown stepped, 45 lap stripe designs made possible by selective control of the needles. The half-hose shows the stripes extending throughout the leg and foot portions thereof though, if desired, the stripes may be omitted from certain portions as in the 50 sole. During heel and toe knitting the striping yarns are idle and consequently do not show.

In Fig. 2 is shown the preferred form of several different fabric structures that overcome the objection of imperfect plating, the numeral 1 indi-

- cating the last plain plated wale; 2 the first lap or wrap stripe wale; 3, 4, 5 the intermediate lap stripe wales; 6 the last lap stripe wale; 7 the following plain plated wale. In this form the plain plating yarn 8 floats across all of the wales of the lap stripe areas, which though shown in Fig. 2 and Figs. 3, 4, 5 and 6 as consisting of the same number of wales, from course to course, may, as disclosed in Fig. 1 at C, vary from course to course.
- 10 The body yarn 9, Fig. 2, on the other hand, is knit-in throughout the lap stripe areas as well as in the plain plated portion of the stocking or fabric. The lap stripe plating yarn 10 is fed to the selected needles by wrapping the said yarn therearound, 15 the rear or non-knitted portions of the wrapping yarn appearing as floats back of the knitted wales. Each lap stripe float passes to the rear of the plain plating yarn float, then around again forward of the said float where it is caught by the 20 first needle in the following course and knit-in together with the main yarn, the lap stripe and plain plating yarn floats thus interlocking. The striped fabric shown in said Fig. 2 is uniform throughout to the extent that there are two knit-in yarns in 25 all of the wales.
- In the form shown in Fig. 3, the first wale, which is plain plated, is indicated by the numeral 11; the first lap stripe wale is indicated by 12, and has three knit-in yarns; 13, 14, 15 are the intermediate 30 lap stripe wales whereat two yarns only are knit-in, the plain plating yarn floating; 16 designates the last lap stripe wale and has three knit-in yarns; 17 designates the next following plain 35 plated wale beyond the lap stripe area. The plain plating yarn 18 is thereby effectively hidden by floating back of the intermediate wales of the lap stripe, being knitted together with the main yarn 19 and lap stripe yarn 20 at the first and last lap stripe wales only of a given course.
- 40 In the form shown in Fig. 4, 21 is the last plain plated wale; 22 is the first lap stripe wale, at which wale all three yarns are shown as being knitted; 23, 24, 25 are the intermediate wales having one knitted yarn only, namely, the lap stripe 45 yarn, there being three floats including the rear stretch of the lap stripe yarn; 26 is the last lap stripe wale, all three yarns being knitted-in in said wale; 27 is the following plain plated wale and is composed of two yarns only. The fabric disclosed 50 in Fig. 4 differs from that shown in Fig. 3 in that the intermediate wales 23, 24, 25 are composed of a single knitted yarn, the plain plating yarn 28 as well as the main or body yarn 29 floating back of and across the intermediate wales 23, 24, 25 of the 55 lap stripe, the lap stripe yarn 30 only, being knitted-in at the said wales.
- Fig. 5 discloses still another form more like the form shown in Fig. 2 than those of Figs. 3 and 4 in some respects; both Figs. 2 and 5 showing fabrics wherein there are not more than two yarns knitted at any wale. In the form disclosed in Fig. 5 the last plain plated wale 31 is followed by the first lap stripe wale 32 adjacent to which are the intermediate wales 33, 34, 35 of the lap stripe area, 60 said intermediate wales being identical with the intermediate wales 23, 24, 25 of Fig. 4, in that the lap stripe yarn alone is knitted the others floating. The last lap stripe wale 36 as well as the first lap stripe wale 32, are formed by floating the plating yarn 38 and knitting the body and lap stripe yarns 39 and 40 respectively. The last wale 37 is plain plated as in the other forms. In this form the plain plating yarn floats and interlocks or passes between the lap stripe float and the knit-in wales of the lap stripe yarn.

In the form of fabric shown in Fig. 6, plain plated wales 41, 42 are followed by intermediate, lap stripe wales 43, 44, 45, such lap stripe wales being, in turn, followed by plain plated wales 46, 47. The plain plated wales are knitted with the plain plating yarn 48 and the body yarn 49; whereas the lap stripe wales are knitted with the lap stripe yarn 50 only, the plain plating and body yarns 48, 49, floating across the intermediate wales. The interlocking of the lap stripe floats 10 with the floats of the plain plating and body yarns is availed of to connect the intermediate wales with the plain plated wales.

It will be understood that in all the forms disclosed, the main or body yarn, the plain plating yarn, and the lap stripe, plating yarn may have different characteristics as to weight, color and quality, cotton, silk and artificial silk ordinarily being used.

The fabric shown in Fig. 7 corresponds to that shown in Fig. 2 excepting that the designs knitted into the fabric are stepped, in other words, the wrap stripe thread 51 is knitted into the fabric at one or two wales (two such wales 52 and 53 being shown) and thereafter is knitted into adjacent wales 54 and 55 only, floating across wales 52 and 53, following which the said wrap stripe thread 51 is knitted into wales 56 and 57 only, floating across wales 52-55 inclusive.

The fabric design disclosed in Fig. 7 has, for 30 illustrative purposes only, been shown and described as corresponding to the form of fabric disclosed in Fig. 2; however, the broken or stepped designs may obviously be knitted into the fabric and either or both body yarns may be floated 35 across some wales and knitted into others as disclosed in Figs. 3-6.

Although a striping yarn has been referred to throughout this specification, it is not the intention to restrict this invention to the use of a single 40 striping yarn as, ordinarily, and as disclosed in the Lawson and Lawson Patent 1,702,608, several such striping or lap stripe, plating yarns are used, certain needles knitting one of the said striping yarns and other needles knitting another such 45 yarn.

In all the forms disclosed, the plain plating and lap stripe plating yarns are knitted, preferably though not necessarily, under tension, as light a tension as possible being maintained on the lap 50 stripe or reinforcing yarn; the body yarn, on the other hand, being free from tension or substantially so.

In the several modifications disclosed herein, float threads are the result of the knitting of 55 the striped fabric, the lap stripe itself leaving floats and, the main or body yarn and the plain plating yarn appearing as floats in certain of the modifications; the floats may, however, be cut, if desired, the cutting aiding the elasticity. 60 The cutting would, preferably, be by an operation subsequent to the knitting of the stocking or other fabric and is therefore not herein disclosed, not forming a necessary part of the invention.

While in the foregoing description, reference 65 has been made to plain plating and plain plated wales, it will be understood that such language is intended to cover, as well, reverse plated areas within or about plain plated areas, "plain plated wales" being merely used to distinguish from 70 wales as herein disclosed, where the lap stripe plating or other yarn or yarns is combined with the body and plain plating yarns.

The invention is not necessarily restricted to the knitting-in of the third yarn by means of the 75

lap stripe method but broadly involves the knitting-in of a third thread or threads by any method and controlling the three or more yarns or threads in such a manner that one or two only of the said three or more yarns are knit-in at certain of the wales, the others floating.

The preferred form, Fig. 2, shows a striping yarn knit-in together with the body yarn, the plain plating yarn floating throughout the 10 striped area; Fig. 3 shows substantially the same arrangement except that the plain plating yarn is also knit-in at the first and last wales of the striped area; Fig. 4 is similar to Fig. 3 except that in the modification disclosed in said Fig. 4 both the main or body yarn and the plain plating 15 yarn float across the wales intermediate the first and last striping wales, i. e., where the striping yarn is knit-in; Fig. 5 the body yarn only is knit-in with the striping yarn at the first and last 20 wales of the stripe, the plain plating yarn floating throughout the stripe and the body yarn across the intermediate wales of the said stripe; Fig. 6 shows the striping yarn alone knit-in in 25 the striping area, the body and plain plating yarns floating.

In Fig. 8 the wrap stripe thread 58 is shown as being knitted into the fabric at wales 59, 60 and 61, being first knitted into wales 60 and 61 only and then being knitted into wale 59 only.

In Fig. 9 the wales 62, 63 and 64 are shown as having incorporated therein wrap stripe threads 65, 66, 67 respectively, the wrap stripe threads 65 and 67 being first knitted into the fabric at wales 62 and 64 after which the thread 66 is knitted into the fabric at wale 63.

In Figs. 8 and 9 the respective plating, body threads 68 and 69 are shown as being knitted into the fabric at some wales and floating across intermediate wales at which wales wrap stripe 40 threads 58, 65, 66 or 67 are knitted.

Referring to Fig. 10, a slight modification is shown wherein a body portion 70 has been knitted with a body yarn 71 and an ornamental area generally designated at 72, of a diamond shaped outline, is knitted from a yarn 73. This fabric is similar to that of Fig. 4 and has the wrapped area knitted solid rather than open at spots as shown at C, Fig. 1. Floats 74 of the body yarn pass behind the ornamental area 72 and other 50 floats 75 of the ornamental yarn pass to the back of the ornamental area and extend between the opposite ends of the courses making up said ornamental area.

All the modifications have in common the idea 55 of floating, at least, one of the body and plain plating yarns to the rear of, at least, some of the striping wales, or, in other words, they all disclose the knitting-in at some of the striping wales, of one yarn or two, not more than two yarns 60 having knitted loops at some of the said striping wales.

Although specific forms of the fabric structure have been disclosed, the invention is not limited 65 to the fabrics specifically described but includes all modifications thereof that fall within the scope of the appended claims.

We claim:

1. A knitted fabric having a body yarn and a 70 wrap thread, such body yarn being floated at some of the wrap stitches or loops, the number of which wrap stitches or loops varies from course to course, some of the wrap stitches or loops each being characterized by the thread being knitted 75 at such loop or stitch and such thread also float-

ing to the next loop or stitch where it is again knitted into the fabric in a following course.

2. A knitted fabric having two body yarns, one of which is a plating yarn, and a wrap thread, a body yarn being floated at some of the wrap 5 stitches or loops, the number of which wrap stitches or loops varies from course to course, some of the wrap stitches or loops each being characterized by the thread being knitted at such loop or stitch and such thread also floating to 10 the next loop or stitch where it is again knitted into the fabric in a following course, and wherein the plating body yarn is knitted together with the other body yarn in every course but not at 15 every wale.

3. A knitted fabric having two body yarns, one of which is a plating yarn, and a wrap thread, a body yarn being floated at some of the wrap 20 stitches or loops, the number of which wrap stitches or loops varies from course to course, some of the wrap stitches or loops each being characterized by the thread being knitted at such loop or stitch and such thread also floating to 25 the next loop or stitch where it is again knitted into the fabric in a following course, and wherein the plating body yarn is knitted together with the other body yarn in every course but not at 30 every wale, and the wrap thread is knitted at some of the stitches with one of the body yarns.

4. A knitted fabric having a body yarn and a wrap thread, such body yarn being floated at some of the wrap stitches or loops, the number of which wrap stitches or loops varies from course to course, some of the wrap stitches or loops each being characterized by the thread being knitted 35 at such loop or stitch and such thread also floating to the next loop or stitch where it is again knitted into the fabric in a following course, and wherein the wrap thread is knitted at some of the 40 stitches, with the said body yarn.

5. A knitted fabric having two body yarns and a wrap thread, one such body yarn being floated at some of the wrap stitches or loops, the number of which wrap stitches or loops varies from course to course, some of the wrap stitches or loops each being characterized by the thread being knitted 45 at such loop or stitch and such thread also floating to the next loop or stitch where it is again knitted into the fabric in a following course, and wherein a wrap thread is knitted together with 50 both of the body yarns at some of the stitches and with one only of the said body yarns at other 55 stitches, at which stitches the non-knitted yarn is floated.

6. A plain knit fabric comprising a main web 55 knit from a body yarn and having an ornamentally configured area with float skips of the body yarn across varying numbers of wales in successive courses of the fabric; and a plain knit fill-in web completely closing the ornamentally configured 60 area, formed from contrasting yarn, said main and fill-in webs being connected only by inter-looping of contiguous loops of the two yarns at the edges of the ornamentally configured area and the contrasting yarn being floated at the 65 back of the fabric between opposite end loops of contiguous courses of the fill-in web.

7. The method of producing ornamented knit fabrics which comprises knitting a plain web 70 from a body yarn with formation of float skips across varying numbers of wales in successive courses of the knitting; and concurrently closing the skips by knitting a fill-in web from a separate contrasting yarn in such manner that only contiguous edge loops of the two webs are intercon- 75

nected, and the contrasting yarn in floated at the back of the fabric between opposite end loops of contiguous courses of said fill-in web.

5. A plain knit fabric comprising a main web knit from a body yarn and having an ornamenteally configured area with float skips of the body yarn in successive courses of the fabric; and a plain knit fill-in web completely closing the ornamenteally configured area, formed from contrasting yarn, said main and fill-in webs being connected only by interloopment of contiguous loops of the two yarns at the edges of the ornamenteally configured area and the contrasting yarn being floated at the back of the fabric be-

tween opposite end loops of contiguous courses of the fill-in web.

9. The method of producing ornamented knit fabrics which comprises knitting a plain web from a body yard with formation of float skips 5 in successive courses of the knitting; and concurrently closing the skips by knitting a fill-in web from a separate contrasting yarn in such manner that only contiguous edge loops of the two webs are interconnected, and the contrasting yarn is 10 floated at the back of the fabric between opposite end loops of contiguous courses of said fill-in web.

JOHN LAWSON.
